(57) **CLAIM**

The ornamental design for a bottle and bottle cap, substantially as shown and described.

DESCRIPTION

FIG. 1 is a perspective view of a bottle and bottle cap, showing our new design;

FIG. 2 is a front view thereof;

FIG. 3 is a back view thereof; and,

FIG. 4 is a top view thereof.

The broken lines in the drawing views are included for purposes of illustrating unclaimed environment only, and forms no part of the claimed design.
